UNITED STATES PATENT OFFICE.

CARL L. HORACK, OF BROOKLYN, NEW YORK, ASSIGNOR TO THE PROVIDENCE STEAM AND GAS-PIPE COMPANY, OF PROVIDENCE, R. I.

AUTOMATIC FIRE-EXTINGUISHER.

SPECIFICATION forming part of Letters Patent No. 292,482, dated January 22, 1884.

Application filed May 9, 1881. (Model.)

To all whom it may concern:

Be it known that I, CARL L. HORACK, of the city of Brooklyn, county of Kings, and State of New York, have invented a new and useful Improvement in Automatic Fire - Extinguishers; and I hereby declare that the following is a full, clear, and exact description of the same, reference being had to the accompanying drawings, forming part of this specification.

This invention has reference to that class of automatic fire-extinguishers in which the water is retained by a seal formed by soldering a cap over the discharge-orifices by a solder composed of a material that will melt at a low temperature, and thus release the seal on the breaking out of a fire and allow the water to be discharged on the fire.

The invention consists in forming the distributor of a bent section of pipe perforated upon its outer curved side, the perforations being closed by a cap constructed to closely fit the perforated portion of said pipe.

Figure 1 is a view of an automatic fire-extinguisher consisting of a bent pipe, to each end of which a supply or connecting pipe is secured, the bent pipe being perforated to form a distributor, and such perforations being covered by a closely-fitting cap or cover soldered to the pipe by a solder fusible at a low temperature. Fig. 2 is a sectional view, showing the perforations in the tube. Fig. 3 is one of the closely-fitting caps soldered to the perforated device shown in Fig. 1. Fig. 4 represents a piece of perforated pipe, showing part of the perforations covered by a closely-fitting cap secured by solder, part of the cap being broken away to show the perforations in the pipe.

In the drawings, *a* represents a perforated 40 sprinkler or distributor, constructed to distribute the water in a spray on the fire.

b is a cap, made of such form as will closely fit the distributor, so as to leave as little space as possible between the cap and the distributor. This cap is secured to the distributor by means of a solder fusible at a low temperature, so that a water-tight joint is made and all possibility of a leak is prevented.

The object of making a cap to fit the distributor closely is to keep the water from contact with the soldered joint or to reduce the quantity of water between the distributor and the cap, and thus prevent the absorption of heat by the water, and insure the prompt action of the distributor in the case of fire. This distributor is strong and inexpensive, and may be readily applied to a line of pipe, and the cap can be easily and quickly applied to the distributor.

I prefer to solder the cap at the edges to the distributor; but the same may be secured by solder over the whole surface of the cap.

Having thus described my invention, I claim as new and desire to secure by Letters Patent— 65

A distributor for fire-extinguishers, consisting, substantially as before set forth, of a bent section of pipe perforated upon its outer curved side, in combination with a cap constructed to closely fit the perforated portion 70 of the distributor and be secured theron by fusible solder.

C. L. HORACK.
